UNITED STATES PATENT OFFICE.

CHARLES A. BLUME, OF ROCKY FORD, COLORADO, ASSIGNOR TO THE WHIRL POOL WATER MOTOR COMPANY, OF ROCKY FORD, COLORADO, A CORPORATION OF COLORADO.

WATER MOTOR.

Application filed September 4, 1924. Serial No. 735,919.

To all whom it may concern:

Be it known that I, CHARLES A. BLUME, a citizen of the United States, and a resident of Rocky Ford, in the county of Otero and

5 State of Colorado, have invented certain new and useful Improvements in Water Motors, of which the following is a specification.

This invention relates to water motors and 10 has for its object the provision of a device in which the water will be directed towards the upper portions of the blades of the motor at different angles, so that after the blades have received the impact of the water 15 streams at a higher level the second series of streams at a lower level and at different angles are directed on the blades with each spirally curved blade forming a whirlpool effect and furnishing the suction force in 20 completing the circuit of the motor through the blades of the motor.

The angular direction of the flow of the streams of water against the blades and the curvature in depth of the passages between 25 the blades causes the water to act upon one face only of each blade thus eliminating back pressure of the water on the opposite face of the blade, the points of escape being so designed whereby the water will be discharged freely without retarding the speed 30 of the motor.

A further object of the invention is the provision of a water motor having a plurality of streams directed against the blades of 35 the motor at different angles and at different levels and in which a chamber located above the motor is adapted to equalize the air pressure on the motor during operation.

A still further object of the invention is 40 the provision of a three-point over-head suspension for the motor.

This invention will be best understood 45 from a consideration of the following detailed description, in view of the accompanying drawing forming a part of the specification; nevertheless it is to be understood that the invention is not confined to the disclosure, being susceptible of such changes and modifications which shall define no material departure from the salient features of 50 the invention as expressed in the appended claims.

In the drawings:

Figure 1 is a vertical section of the motor 55 in operative position.

Figure 2 is a horizontal section taken along the line 2—2 of Figure 1.

Figure 3 is a view in perspective of an air shaft and its associated controlling gate.

Referring more particularly to the drawings, 60 1 designates a flume adapted to receive water from a higher level and supported upon columns or a foundation 2 made of any suitable material and so constructed as to provide a passage for the outlet of the water 65 from the water motor. The floor 3 of the flume 1 is provided with an opening 4 through which is inserted the discharge end 5 of the motor casing 6.

The motor casing is frusto-conically 70 shaped with the lower enlarged end depending below the floor 3 and supported by means of an angle iron ring 7 bolted to the casing 6 and to a ring or closure 8 for the opening 4 in the floor 3. The ring 8 is of 75 sufficient extent to overlap the bottom 3 of the flume at points beyond the periphery of said opening.

Connected in any approved manner with the outer wall of the motor casing 6 is a 80 flange 9 resting on the ring 8 and provided with tangentially disposed conduits 10 which open into the wall of the casing 6 above the flange 9 for directing the water from the flume upon the blades 11 of the motor 12. 85 Located at a higher level than the tangentially disposed conduits 10 is an annular shelf 13 having alternate passages 14 directed tangentially toward the blades of the motor. Between the passages 14 are located 90 other passages 15 having their bases 16 disposed slightly above the shelf or bases 13 of the passages 14.

The bases 16 of the passages 15 are inclined upwardly and are higher at their 95 inner ends than at their outer ends so that the water directed by such passages is forced slightly upwardly before it strikes the blades 11. The bottoms of the passages 14 are inclined slightly downwardly and are therefore located at a lower level than the passages 15 and tend to direct the water from the flume 1 not only tangentially but downwardly against the blades.

It must be borne in mind that while the various walls of the casing forming the water passages to the motor may be made separately the passages may be cast integrally with said casing.

A cylindrical air shaft 17 located cen- 110

trally of the flume and suspended from the top 18 of the flume by means of flanges 19 has its base 20 rigidly secured to the upper end of the casing 6 and above the water passages 14 and 15. The upper end, as shown at 21, projects through the opening in the top 18 of the flume 1 and is provided with a closure 22. The closure 22 is provided with a bearing 23 for a shaft 24 of the motor 12. The shaft is provided with a collar 25 which is rigidly secured to the same and which rests upon the bearing 23 of the closure 22. A web 26 secured to or integrally formed with the inner wall of the cylinder 17 adjacent its lower end is provided with a bearing 27 through which shaft 24 passes and supports the sleeve 28 rigidly connected with said shaft. The bottom 20 of the cylinder or air shaft 17 is provided with a bearing 29 for supporting a collar 30 rigidly connected with the shaft 24. It will be seen from this construction that the shaft 24 and motor 12 are supported at three points, that is the respective bearings 23, 27 and 29.

25 The lower end 31 of the air shaft 17 is reduced in diameter and is adapted to receive a leather washer 32 upon its exterior surface over which is adapted to ride a cylindrical gate 33. This washer is provided to prevent the passage of water past the gate after said gate has been closed. The gate 33 encircles the reduced portion 31 of the air shaft 17 and is carried by rods 34 and 35 which are slidably in perforated 35 lugs 36 projecting from the outer walls of the cylinder 17. A semi-circular support 37 is secured at its upper end 38 to the rod 34 while its lower end 39 is secured to rod 35. The upper end of the support 37 embraces the cylindrical shaft 17 in spaced relation and is adapted to connect rod 34 with 40 35 for simultaneous raising or lowering of said rods. Rod 34 passes through a perforation in the flange 19 on the air shaft 17 and also through a perforation in the top 18 of the flume 1 and is provided at its outer end with a rack 40 engaged by a spur gear 41. The spur gear is adapted to be operated manually and through any form 45 of suitable mechanism well known in the art.

50 It will be seen (Figure 1) that the lower ends of the rods 34 and 35 are secured to perforated ears 42 located at diametrically opposite points on the outer wall of the gate 33. When it is desired to stop the motor it is only necessary to rotate the gear 41 and cause the rods 34 and 35 to be depressed whereby the gate will be lowered and completely shut off or control the flow of water 55 from the flume 1 through the various passages 10, 14 and 15. By partially lowering the gate 33 the amount of water entering the various passages 14 and 15 may be limited accordingly.

55 The base 20 of the cylindrical member 17

is provided with openings 43 above which are provided threaded bosses 44. Into said bosses are screwed air conduits 45. These conduits pass upwardly through bearings 46 formed in the web 26 and terminate adjacent the upper end of the cylindrical air shaft 17. The air shaft 17 is substantially sealed by the top 22 and bottom 20. It will be seen that these air shafts form a direct passage between the upper end of the casing 6 75 where the water passages 14 and 15 are formed and are adapted to equalize the air pressure at these points through the air shaft 17.

The upper end of the motor 12 is of smaller diameter than the lower end and the blades 11 are curved along the lines of a spiral with the adjacent faces of a pair of blades forming a channel 48 and opening directly into the pit 49 below the casing 6. 80 It will be seen that the blades are so constructed and spaced from each other that when the water strikes the blades when passing through the various channels it will exert its force upon the blades and be readily discharged through the channels 48 and the large open ends of the motor without causing the water to be dragged around with the motor and thereby lessening the power of the same. The conduits 10 are 85 adapted to provide a whirlpool motion to the water as it enters and acts upon the blades.

The device as constructed for practical purposes will have approximately 192 points 100 of impact of the water against the blades since there are 24 separate openings through which the water is directed against the eight blades during a complete revolution of the motor. Due to the various levels at which 105 the water enters the casing 6 and the various angular dispositions of the streams of water the water will not be allowed to stack up at any point since a small amount of water only is required and having a maximum 110 striking force at all points against the blades.

What I claim is:

1. A water motor comprising a flume, an opening in the bottom of the flume, a motor casing projecting through said opening and open at its lower ends, a motor revolubly mounted in the casing and provided with blades, a plurality of tangential passages connecting the flume with the interior of the motor casing, a second series of tangentially disposed passages located above the first mentioned passages and connecting the interior of the casing with the flume, alternate passages of the second series being inclined downwardly.

2. A water motor comprising a flume, an opening in the bottom of the flume, a motor casing projecting through said opening and open at its lower end, a motor revolubly 130

5 mounted in the casing and provided with blades, a plurality of tangential passages connecting the flume with the interior of the motor casing, a second series of tangentially disposed passages located above the first mentioned passages and connecting the interior of the casing with the flume, alternate passages of the second series of 10 passages being located at a higher level than the remaining passages of said series.

3. A water motor comprising a flume, an opening in the bottom of the flume, a motor casing projecting through said opening and open at its lower end, a motor revolvably 15 mounted in the casing and provided with blades, a plurality of tangential passages connecting the flume with the interior of the motor casing, a second series of tangentially disposed passages located above the first 20 mentioned passages and connecting the interior of the casing with the flume, alternate passages of the second series of 25 passages being inclined downwardly from their outer ends to their inner ends, the remaining passages of the second series being inclined upwardly from their outer ends to their inner ends.

4. A water motor comprising a flume, an opening in the bottom of the flume, a motor casing projecting through said opening and open at its lower end, a motor revolvably 30 mounted in the casing and provided with blades, a plurality of tangential passages connecting the flume with the interior of the motor casing, a second series of tangentially 35 disposed passages located above the first mentioned passages and connecting the in-

terior of the casing with the flume, an air shaft secured to the upper end of the motor casing, and air passages connecting the interior of the motor casing with the air shaft, alternate passages of the second series being located in a different plane from the remaining passages.

5. A water motor comprising a flume, an opening in the bottom of the flume, a motor casing projecting through said opening and open at its lower end, a motor revolvably mounted in the casing and provided with blades, a plurality of tangential passages connecting the flume with the interior of the motor casing, a second series of tangentially disposed passages located above the first mentioned passages and connecting the interior of the casing with the flume, a sealed 55 air shaft secured to the upper end of the motor casing, conduits mounted within the air shaft in open communication with the upper end of the air shaft and terminating short of the closure of the air shaft.

6. A water motor comprising a casing, a rotor within said casing provided with blades, passages located at different levels and connecting the interior of the motor with the exterior, a shaft connected with the rotor, a casing forming an air shaft located above the motor casing and provided with bearings at its opposite closed end, and a bearing intermediate its ends supporting the shaft, and means on the shaft above 65 said bearing adapted to support the shaft and rotor.

CHARLES A. BLUME.
